UNITED STATES PATENT OFFICE.

GEORGE M. WILLIS, OF CHICAGO, ILLINOIS.

THERMOSTATIC RADIATOR-SHUTTER CONTROL.

1,368,673.

Specification of Letters Patent. Patented Feb. 15, 1921.

Application filed April 23, 1917. Serial No. 163,782.

To all whom it may concern:

Be it known that I, GEORGE M. WILLIS, a citizen of the United States, residing at Chicago, in the county of Cook and State 5 of Illinois, have invented certain new and useful Improvements in Thermostatic Radiator-Shutter Controls, of which the following is a full, clear, concise, and exact description, reference being had to the accompanying drawings, forming a part of this 10 specification.

The present invention relates to radiators for internal combustion engines and has 15 particular reference to an automatic thermally controlled shutter for use in connection therewith.

An object of my invention is to provide a new and improved automatic thermally controlled mechanism for regulating the 20 amount of air to reach the radiator structure whereby to maintain the cooling medium at a constant temperature best adapted to suit the working conditions of the engine.

I am aware that manual means for controlling the admission of air to the radiator has been suggested, but in using manual 25 means the requirement of the engine under varying working conditions must be handled to the best judgment of the operator, which at its best can give results only partly effective.

I am also aware that automatic means has been placed in use but such means is usually 30 delicate, hard to reach and to adjust, incapable of but a small scope of movement, necessitating additional mechanism to increase the movement of same, and is therefore prohibitive in cost and upkeep.

Another object of my invention is to provide a device of the character described in 35 which the thermostatic member is located entirely within the water jacket of the radiator, is simple in construction and cheap 40 to manufacture and install.

A further object is to obtain the most accurate and effective results by actually 45 submerging the thermostat in the liquid within the head of the radiator.

Other objects and advantages of my invention not hereinbefore pointed out will 50 appear from the following detailed descrip-

tion, taken with an inspection of the accompanying drawings, in which—

Figure 1 is a fragmental front elevation 55 of a radiator, showing my improved thermal controlling means applied thereto;

Fig. 2 is a vertical side elevation of the same;

Fig. 3 is a modified form of the invention. 6

Referring more particularly to the drawings, wherein similar characters of reference designate like and corresponding parts throughout the various views, 10 designates in its entirety a body of a standard radiator, the same having a water jacket 11 completely encircling an active surface 12 which is composed of a plurality of interconnected tubular members serving to afford circulation of the cooling medium. The jacket 15 70 70 is provided with a top portion which I shall hereinafter term the head 13. The usual filling inlet 14 is provided in the head 13. Outside of the side portions of the jacket 11 an outer wall 15 is usually provided affording a space 16 which I utilize in one of the modified forms of my invention 75 which I shall refer to later.

The thermostat of my invention comprises an arm designated A in its entirety and 80 composed of a pair of strips 17 and 18 of dissimilar metals, one end of the arm being rigidly secured to the head 13 by means of rivets 19 or the like. The arm extends transversely of the head and is located beneath the water level therein, the free end 85 of the arm having a vertical rod 20 extending therefrom, said rod passing through a tubular extension 21 formed on the head 13. The tubular extension is provided in 90 this instance owing to the peculiar shape of the head of the radiator. This prevents the liquid contents of the head from passing out around the rod 20. Of course, it is to be understood that the rod fits snugly within 95 the opening in the tube so that a minimum space is provided between the rod and tube. A slot 22 is provided in the free end of the arm through which the rod 20 engages, said rod having an enlargement 23 thereon and a 100 nut 24 so as to allow for expansion and contraction longitudinally of the strip without binding the rod 20.

The free end of the rod 20 is bent for-

wardly to provide an extension arm 25. The free end of the arm 25 is pivotally connected with a link 26, said link being in turn pivotally connected with a rod 27, said rod 5 having connections at the points 28 with a plurality of hingedly mounted shutter sections 29 mounted on the front of the radiator. It will be apparent that when the 10 temperature of the liquid contents of the radiator changes, the free end of the arm A will move causing the rod 20 to be reciprocated vertically, in turn actuating the rod 27 which serves to open or close the shutter sections 29, said shutter sections being located over the active surface of the 15 radiator and thereby controlling the admission of air thereto.

It will be understood that, if desired, an outer hood may be placed over the head 20, 13 and extension tube 21 by extending the side walls 15 of the radiator body so that the outward appearance of the radiator is not changed.

In Fig. 3 I have illustrated a modified 25 form of my invention. In this instance the arm A is employed, the rod 20, tube 21 and the extension 25 of said arm. However, in this form the rod 20 is lengthened to provide a downwardly extending portion 31 which 30 passes through one of the air pockets 16. The extension 31 passes out through the bottom of the radiator and is bent laterally forward and upward as at 32, the free end thereof being pivotally connected to a link 33 which is in turn pivotally connected to 35 the rod 34 which latter is operatively connected to the separate sections 35. If desired, the outer walls of the radiator body may be extended to cover the projecting 40 portion of the rod 20 and its extensions so as to protect the same and present a finished appearance to the radiator.

I do not limit myself, of course, to the 45 details of construction shown, the principal idea of the invention being to locate a thermostatic arm within the radiator and submerged in the liquid contents thereof so as to control the shutter mechanism. Means other than mechanical means may be employed for imparting movement from the 50 arm to the shutter mechanism, but the means shown is employed in view of its simplicity and the cheapness with which the same may be manufactured and placed upon the market. Of course, the two strips 17 and 18 55 composing the arm A are riveted or otherwise securely connected in parallel relation and said arm is preferably mounted in the position shown in view of the compact ar-

rangement afforded thereby. I reserve the 60 right to make such changes in the detail structure as do not depart from the spirit and scope of the invention as claimed.

I claim:—

1. In a cooling system for an automobile 65 engine, a radiator having a water jacket provided with a head, and an active surface, air pockets along the sides of said jacket, a plurality of shutter sections pivotally mounted on said radiator structure, means 70 to connect said sections for simultaneous operation, a thermostatic arm having one end rigidly connected to said head, said arm being located wholly within the head and adapted to be submerged in the liquid 75 contents thereof, and means extending up through the head and down through one of said air pockets to connect the free end of said thermostatic arm with the lower end 80 of said shutter sections whereby to control the admission of air to the active surface of the radiator.

2. In a cooling system for an automobile 85 engine, a radiator having an active surface, a thermostatic arm in the top of the radiator, said arm extending across the radiator from side to side, one end thereof mounted rigidly on the radiator wall, the opposite end being freely movable in response to temperature changes, a plurality of shutter sections 90 controlling said active surface, a rod operatively connecting the shutter sections together, a shutter operator rod extending through the top of the radiator, its inner end connected directly to the free end of the 95 thermostatic arm, and a link connecting its outer end to said rod to cause the shutters to be adjusted in direct response to the movement of the free end of the thermostatic arm. 100

3. In a cooling system for an automobile engine, a radiator having an active surface, an elongated thermostatic arm in the upper part of the radiator, one end of the arm rigidly mounted at one side of the radiator, the arm extending substantially across the radiator, the opposite end of the arm being freely movable in response to temperature changes, a plurality of shutters for controlling the exposure of said active surface 105 and means movable through a wall of the radiator and connecting said free end of the thermostatic arm to said shutters for direct operation thereof. 110

In witness whereof I hereunto subscribe 115 my name this 20th day of April, A. D. 1917.

GEORGE M. WILLIS.
